UNITED STATES PATENT OFFICE.

LESLIE R. KIEHL, OF RATON, NEW MEXICO.

PUMP.

Application filed January 16, 1924. Serial No. 686,596.

To all whom it may concern:

Be it known that I, LESLIE R. KIEHL, a citizen of the United States, residing at Raton, in the county of Colfax and State 5 of New Mexico, have invented new and useful Improvements in Pumps, of which the following is a specification.

This invention relates to pumps and is an improvement upon the subject matter 10 of patent numbered 1,328,165, granted to me January 13, 1920.

Like the above numbered patent, the present invention aims to provide a pump by means of which water in a pre-heated or 15 partially heated state may be introduced into a steam boiler, so that the temperature in the latter will not be appreciably reduced.

In addition, the present invention aims to provide means included in the pump to 20 reduce leakage past the pump piston and to overcome and release leakage at each end of the piston stroke.

With the above and other objects in view, the invention further includes the following 25 novel features and details of construction, to be hereinafter more fully described, illustrated in the accompanying drawing and pointed out in the appended claims.

In the drawing the figure shown represents 30 a sectional view of a pump constructed in accordance with the invention and illustrating its position in use.

Referring to the drawing in detail wherein like characters of reference denote corresponding parts, the pump as shown includes 35 a cylinder 10 which is open at one end and provided adjacent said end with a steam inlet port or ports 11. This end of the cylinder is arranged within a boiler, a 40 portion of which is indicated at 12.

The cylinder 10 further includes a water inlet port or ports 13, while surrounding the cylinder and communicating with the latter through the port 13 is a tank or reservoir 45 14 so that water may be supplied to the interior of the pump cylinder. It is of course obvious that other suitable means may be provided for this purpose.

Operating within the cylinder 10 is a piston 50 which includes spaced heads 15 and 16, both of which are provided with suitable packing rings 17. The head 15 is of an appreciable length and at each end of this head there is provided annular grooves or 55 chambers 18. These grooves or chambers may be formed in any suitable manner, such

as by providing auxiliary head sections 19 spaced from the main portion or body of the head and secured to the piston rod 21 by any suitable means. The head 16 is 60 spaced from the head 15 and this space provides a water and steam chamber wherein water and steam are mixed to reduce the temperature of the former before the water is transferred from the tank 14 to the boiler. 65 The head 16 like the head 15 is provided with an annular groove or chamber 22 which is formed by spacing an auxiliary head 23 from a main portion of the head, the rod 21 extending through and connecting the head 70 16 and its auxiliary portion 23.

The rod 21 extends through a suitable packing gland 24 provided at the outer closed end of the cylinder 10 and this end of the cylinder is in communication with 75 the boiler through a steam pipe 25 which is controlled by a valve 26. Steam pressure upon opposite sides of the pistons may thus be equalized.

By means of the construction shown and 80 described, leakage past the piston heads will be reduced during the piston stroke and released at each end of the stroke, while leakage at each end of the stroke will be overcome. The release of leakage is effected 85 through the register of the grooves or chambers 18 and 22 with the ports 27 and 28, as the water space between the heads 15 and 16 will register with the release port 28 before registering with the water inlet port 90 13, the said port 28 acting to release steam from the pump both on its working and its return stroke.

As shown in the drawings, the piston heads are in position to deliver water to 95 the boiler and when said heads are moved outward or to the left of the figure, the space between the heads 15 and 16 will register with the release port 28 and deliver steam to the tank or reservoir 14, continued 100 movement bringing the groove 22 into register with said port for the escape of possible leakage, the space between said heads 15 and 16 then moving into register with the port 13, so that the cylinder will receive water from the tank. On the return stroke this water is delivered to the boiler 12 through port 11, leakage escaping from the groove 18 through the ports 27 and 28.

The invention is susceptible of various 110 changes in its form, proportions and minor details of construction and the right is here-

in reserved to make such changes as properly fall within the scope of the appended claims.

Having described the invention what is claimed is:—

1. The combination with a steam boiler and a source of water supply, of a pump arranged to transfer water from the source of supply to the boiler, means whereby steam 10 from the boiler will be mixed with the water before the latter enters the boiler and means included in the pump to reduce leakage during the pump stroke and release leakage at each end of the stroke.
2. The combination with a steam boiler and a source of water supply, of a pump arranged to transfer water from the source of supply to the boiler, a reciprocatory piston included in said pump, a collecting 20 groove for said piston and spaced release ports in said pump, whereby leakage dur-

ing the pump stroke will be reduced and said leakage released at the end of the stroke.

3. The combination with a steam boiler, of a pump including a cylinder having a port at one end for communication with the boiler, a water reservoir, said pump cylinder also having a water inlet port spaced from the first mentioned port for communication with the reservoir, said cylinder being further provided with spaced release ports upon opposite sides of the water inlet port, spaced piston heads operating within the cylinder and providing a water and steam mixing chamber between said heads, and said heads having collecting grooves therein for register with the release ports to release leakage at each end of the piston stroke.

In testimony whereof I affix my signature.

LESLIE R. KIEHL.
